UNITED STATES PATENT OFFICE.

ENOS M. CLOUGH, OF LAKE VILLAGE, ASSIGNOR OF ONE-HALF TO ALDEN R. TINKHAM, OF LANCASTER, NEW HAMPSHIRE.

LATCH FOR SLIDING DOORS.

SPECIFICATION forming part of Letters Patent No. 275,149, dated April 3, 1883.

Application filed October 31, 1882. (Model.)

To all whom it may concern:

Be it known that I, ENOS M. CLOUGH, of Lake Village, in the county of Belknap and State of New Hampshire, have invented an Improved Handle and Latch for Car-Doors; and I do hereby declare that the following is a full and exact description thereof, reference being had to the accompanying drawings, making part of this specification.

10 Figure 1 is a side view of a car-door as mounted on a side of a freight car and provided with my improved handle and latch; Fig. 2, a section of the door and handle in a plane indicated by the line xx , Fig. 1; Fig. 3, 15 a section in a plane indicated by the line yy , Fig. 1.

Like letters designate corresponding parts in all the figures.

My improved handle and latch are applied 20 to sliding doors, and are intended especially for the sliding doors of freight-cars, ordinarily to be used on the inside thereof, so as to be self-locking and self-unlocking by merely acting on the handle to close and open the door.

25 The objects to be gained by the construction are simplicity and cheapness of construction, strength and durability in use, and convenience and certainty in action.

For the latch A, I employ a simple straight 30 elastic strip of metal attached to the door B at aa by screws or bolts, and having a hook or shoulder-catch, b, to catch over a catch-bar, c, on the door-jamb C.

The handle D is pivoted at its two ends to 35 bearings dd , projecting outward from a plate, E, which is secured to the door by screws cc .

or otherwise. In order to unhook the latch A, a projection, f, on one end of the handle extends therefrom back behind the latch, so as to force the said latch outward by the tilting or rocking of the handle in the proper direction, which is the direction in which the hand presses the handle in the act of pushing back and opening the door. The handle is allowed to rock in its bearings in that direction far 40 enough to raise the latch away from the catch-bar, and in the other direction far enough to allow the latch to catch completely over the catch-bar. Since the sliding of the door requires a considerable exertion of force, this 45 handle should be strong and firm, notwithstanding this slight rocking movement. I therefore widen both bearing ends gg thereof in both directions into the shape of rockers, as shown, so as to form stops of considerable 50 length and abundant strength to bear against the sides of the plate E. Thus I gain fully 55 all the purposes and advantages above set forth.

What I claim as new, and desire to secure by 60 Letters Patent, is—

The combination of the flexible elastic latch A, the plate E, provided with bearings dd , and the rocking handle D, provided with the latch-lifting projection f and the doubly-extended stops gg , substantially as and for the purpose herein specified.

ENOS M. CLOUGH.
